UNITED STATES PATENT OFFICE.

JAMES J. HARTLEY AND FRANK C. DE REAMER, OF SCHENECTADY, NEW YORK, ASSIGNORS TO GENERAL ELECTRIC COMPANY, A CORPORATION OF NEW YORK.

ATTACHING-PLUG AND WALL-RECEPTACLE.

No. 848,902.

Specification of Letters Patent.

Patented April 2, 1907.

Application filed April 22, 1905. Serial No. 256,884.

To all whom it may concern:

Be it known that we, JAMES J. HARTLEY and FRANK C. DE REAMER, citizens of the United States, residing at Schenectady, county of Schenectady, State of New York, have invented certain new and useful Improvements in Attaching-Plugs and Wall-Receptacles, of which the following is a specification.

This invention relates to detachable couplings for electric conductors; and its object is to provide an attaching-plug and a flush wall or floor receptacle having certain features of novelty which will be described in detail and particularly pointed out in the claims.

The plug comprises an outer section or body having a central core and a chamber in one end to receive a head carrying two metallic pins which have binding-screws located inside said chamber. The receptacle comprises a face-plate having two apertures to receive the pins and a base secured to the face-plate and containing two pockets in line with said apertures. In each pocket is a metallic socket to receive a pin, provided with a spring-contact connected with a binding-screw.

In the accompanying drawings, Figure 1 is a central section of the plug and receptacle. Fig. 2 is a top plan view of the head of the plug. Fig. 3 is a top plan view of the base with the face-plate removed.

The body 1 of the plug is of any suitable size and shape. It is made, preferably, of hard rubber and has a central bore 2, which communicates at one end with a chamber 3, into the open end of which is screwed a head 4, also of hard rubber or the like. Two metallic pins 5 have shanks which are inserted through holes in the head, being preferably provided with collars 6, countersunk into the outer surface of said head. The inner ends of the shanks are flush with the inner surface of the head and are drilled and tapped to receive the screws 7, which secure to them the metallic plates 8, carrying the binding-screws 9. The two pins are preferably located at diametrically opposite points in the head, and between them is a circular barrier 4', having notches to permit the wires led in through the central bore 2 to be readily attached to the binding-screws 9.

The pins are split to give them resiliency

and are preferably provided with enlarged ends, as shown.

The receptacle comprises a face-plate 10, preferably of metal and provided with two apertures spaced to receive the two pins and provided with bushings 11, of hard rubber or the like. A base 12, of porcelain or other insulating material, is secured to the back of the face-plate by means of screws 13, which enter tapped holes in two metallic plates 14, which in turn are fastened to the base by long screws 15, passing through said base and tapped into the plates 14, said plates being let in flush with the outer surface of the base.

Two pockets 16 are formed in the base in line with the two apertures in the face-plate. In each pocket is a metallic socket 17, adapted to receive the end of a plug. A slot is cut in the wall of each socket on one side to permit a spring-tongue 18 to project through it into the path of a pin, so as to make good contact with said pin when it is inserted. The tongue has a flange which is clamped beneath the socket by the screw 19, which fastens the latter in its place in the pocket. A strip 20 is also clamped under the head of this screw and extends across to a point under a shallow recess 21, formed in the top of the base. In this recess is a metallic piece 22, carrying a binding-screw 23. A screw 24 connects the strip 20 with the piece 22. From one end of the recess a hole 25 passes to the bottom of the base to permit one of the line conductors to be brought in and secured by the binding-screw 23. By means of the piece 22, the screw 24, the strip 20, and the screw 19 this line conductor is placed in electrical connection with the socket 17 and the tongue 18. When the two pins are in place in their sockets, the two line conductors will be connected with the two branch conductors leading into the plug.

By taking out the screws 13 the face-plate can be removed when it is desired to have access to the terminals of the line conductors. Similarly, by unscrewing the plug from the head the terminals of the branch conductors are rendered accessible.

What we claim as new, and desire to secure by Letters Patent of the United States, is—

1. In a coupling for electric conductors, the combination with an insulating-base pro-

vided with pockets, of metallic sockets secured in said pockets by screws passing through the base, and spring-tongues secured to said sockets and projecting into the same.

5 2. In a coupling for electric conductors, the combination with a base of insulation having two pockets, of a metallic socket in each pocket having a slot in one side, and a

10 spring-tongue projecting through said slot and having a flange clamped beneath said socket.

3. In a coupling for electric conductors the combination of an insulating-base having 15 in the front side two pockets and two re-

cesses, metallic sockets located in said pockets and terminal connections located in said recesses, bridging-strips on the back side of the base, and screws extending through the base and connecting the ends of each strip ²⁰ respectively with a socket and a terminal connection.

In witness whereof we have hereunto set our hands this 21st day of April, 1905.

JAMES J. HARTLEY.
FRANK C. DE REAMER.
